UNITED STATES PATENT OFFICE.

FINDLEY E. CLELAND AND EDWARD B. MURRAY, OF DES MOINES, IOWA,
ASSIGNORS OF ONE-THIRD TO JOSEPH GASS, OF DES MOINES, IOWA.

INSULATING-JOINT FOR PIPES.

SPECIFICATION forming part of Letters Patent No. 707,303, dated August 19, 1902.

Application filed March 10, 1902. Serial No. 97,421. (No model.)

To all whom it may concern:

Be it known that we, FINDLEY E. CLELAND and EDWARD B. MURRAY, citizens of the United States, residing at Des Moines, in the county of Polk and State of Iowa, have invented certain new and useful Improvements in Insulating-Joints for Pipes, of which the following is a specification.

Our objects are to provide a joint especially designed for use in connection with gas-pipes, which joint shall be of simple, durable, and inexpensive construction and readily and quickly applied to a gas-pipe at any point that is readily accessible, preferably near a gas-meter within the building to which it is applied; and our object is, further, to provide a joint of this class that when applied to a gas-pipe leading from a building to the ground will prevent the pipe from becoming "grounded," so that in the event that electric wires within the building come in contact with the gas-pipe the current cannot pass to the ground nor flow through the pipe, and hence the pipe cannot be burned by an electrical current; and our object is, further, in this connection to provide means, together with the insulating-joint, whereby in the event that an electric arc should be established through the insulating-joint the arc will be quickly extinguished, so that even in the event of excessive electrical discharges, such as might be caused by lightning, it cannot flow from the electric wires within the building to the ground, or in the event that a flash should pass through the insulating-joint the arc thus established will be quickly extinguished.

Our invention consists in certain details in the construction, arrangement, and combination of the various parts of the device whereby the objects contemplated are attained, as hereinafter more fully set forth, pointed out in our claims, and illustrated in the accompanying drawings, in which—

Figure 1 shows in perspective two pipes connected by our improved insulating-joint. Fig. 2 shows an inside end view of one of the parts of the insulating-joint with the permanent magnets in position therein, and Fig. 3 shows a longitudinal sectional view through

the joint and through the adjacent ends of two metal pipes.

Referring to the accompanying drawings, we have used the reference-numeral 10 to indicate one of the metal service-pipes, provided at its end with an outwardly-projecting flange 11. The other pipe (indicated by the numeral 12) may, if desired, be of smaller diameter and is provided with a similar outwardly-projecting flange 13.

The insulating-joint proper is composed of two similar blocks, each block having on its inner face a recess large enough to admit the flange of the pipe and on its outer face having an opening arranged concentrically relative to the recess and fitting the pipe proper, so that the pipe may be inserted through the inner face of the block and the flange of the pipe rest against the bottom of the recess, while the body portion of the pipe projects through the opening.

The numeral 14 indicates the block, and 15 the recess on its inner face. If the pipe is thus placed in position, we fill the recess on top of the flange with an insulating substance, preferably sulfur. This insulator is indicated by the numeral 16, and an opening 17 is provided through its central portion to establish communication through the pipe and block.

On the inner face of one of the blocks 14 we have placed a series of permanent horseshoe-magnets 18, with their ends arranged in position surrounding the opening 17. These magnets are embedded in porcelain blocks 14, and the sulfur filler 16 surrounds the ends, thus firmly holding them in position.

The numeral 19 indicates an insulating packing-sheet having an opening through its center and placed between the blocks 14, and the blocks are held together by means of the bolts 20, passed through them and provided with the nuts 21 on their ends. In connecting an insulating-joint of this class with the adjacent ends of two service-pipes we first form on the ends of the pipe the flanges 11 and 13. We then place the pipes in the blocks. When this is done, the sulfur is applied, preferably in melted form, and is run into position to fill the recesses in the blocks,

a core of some sort being provided, so that an opening is left through the sulfur fillers. Obviously this filler will thoroughly seal the cracks or joints within the blocks and rigidly secure the pipes to the blocks, so that there can be no leakage from the pipes to the outer surfaces of the blocks. Then the insulating-sheet 19 is placed between the blocks and the opening in its center in line with the opening through the fillers, and then the bolts 20 are inserted and the nuts 21 are tightly screwed to position, thus preventing leakage between the blocks. The joint is applied to that portion of the pipe which stands in a substantially vertical position, so that no moisture can accumulate in the joint. In practical use it is obvious that where a joint of this class is applied to a pipe there can be no electrical connection between the pipes 10 and 12, and even though electrical service-wires are connected with the pipes in a building the said pipes cannot be grounded, and hence as the current cannot flow through them the pipes cannot become burned by said electrical currents. Furthermore, in the event that an unusually large electrical current—such, for instance, as a lightning discharge—should in some way become connected with the service-pipes and should be of such intensity to be capable of establishing an arc through the insulating-joints then the action of the permanent magnets would tend to immediately dissipate the arc and prevent it from burning the pipes. Also our improved insulating-joint is especially designed for use on gas-service pipes and may obviously be applied to any kind of pipes that might serve as conductors of electricity, and the insulating-blocks may be made of porcelain or any other suitable insulating material, and the

fillers need not be made of sulfur; but any insulating material that is readily melted could be used in place of the sulfur.

Having thus described our invention, what we claim, and desire to secure by Letters Patent of the United States therefor, is—

1. An improved insulating-joint for pipes, comprising in combination two pipes having flanged adjacent ends, two insulating-blocks having openings in their outer faces to admit the pipes and recesses on the inner faces to receive the flanges, insulating-fillers in said recesses having central openings therein in alignment with the pipes, an insulating packing-sheet having a central opening placed between the blocks, and means for clamping said blocks together. 55

2. In a device of the class described, the combination of two pipes having flanges at their ends, two insulator-blocks having openings extending through them and recesses surrounding said openings in their inner faces with the flanges resting in said recesses, insulating-fillers in said recesses, said fillers having openings therein, a number of permanent horseshoe-magnets embedded in the inner face of one of said blocks and having the insulating-filler surrounding the end portions and having their ends extending to the opening in the insulating-filler, an insulating-sheet having a central opening placed between the insulating-blocks, bolts passed through the insulating-blocks and the nuts on said bolts, substantially as and for the purposes stated. 70
